[57] **CLAIM**

The ornamental design for a magnetic resonance imaging coil bracket, as shown and described.

DESCRIPTION

FIG. 1 is a perspective view of a first embodiment of a magnetic resonance imaging coil bracket showing my new design;

FIG. 2 is a right side elevational view with the left side being a mirror image thereof;

FIG. 3 is a front elevational view thereof;

FIG. 4 is a rear elevational view thereof;

FIG. 5 is a top view thereof;

FIG. 6 is a bottom view thereof common to the first embodiment and a second embodiment;

FIG. 7 is a right side elevational view of the second embodiment thereof with the left side being a mirror image thereof;

FIG. 8 is a front elevational view thereof;

FIG. 9 is a rear elevational view thereof; and,

FIG. 10 is a top view thereof.

The broken line showing of a clamp in FIGS. 2, 5, 7, and 8 is for illustrative purposes only and forms no part of the claimed design.
